US0D1014278S

(12) **United States Design Patent** (10) Patent No.: **US D1,014,278 S**
(45) Date of Patent: ** Feb. 13, 2024

(54) **CUP LID**

(71) Applicant: **Shenzhen Crastal Technology CO. LTD**, Shenzhen (CN)

(72) Inventors: **George Mohan Zhang**, Shenzhen (CA); **Zhen Sun**, Shenzhen (CN); **Chijing Ni**, Shenzhen (CN)

(73) Assignee: **SHENZHEN CRASTAL TECHNOLOGY CO. LTD**, Guangdong (CN)

(**) Term: **15 Years**

(21) Appl. No.: **29/840,020**

(22) Filed: **May 25, 2022**

(51) LOC (14) Cl. **09-01**

(52) U.S. Cl.

USPC **D9/608**; D9/645; D9/451

CLAIM

The ornamental design for a cup lid, as shown and described.

DESCRIPTION

FIG. 1 is a front and top perspective view of a cup lid, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the cup lid that form no part of the claimed design.

1 Claim, 8 Drawing Sheets
